UNITED STATES PATENT OFFICE

CLYDE L. SMITH AND CORNELIUS B. WATSON, OF CHICAGO, ILLINOIS

OIL FRACTIONATING APPARATUS

Application filed February 28, 1928. Serial No. 257,696.

This invention relates to improvements in fractionating apparatus of the type employed in connection with the refining of petroleum oils or other materials capable of being physically separated or fractionated in response to varying control temperatures, and one of the outstanding objects of the invention resides in the provision of an improved type of fractionating tower having 10 features of construction which admit of very close separation between fractions of different boiling points so that when the apparatus is handling hydrocarbon oils in vapor form the gasoline fraction or fractions may be 15 sharply separated from the heavier kerosene fractions or other heavier fractions of higher boiling point, to the end of obtaining the maximum recovery from a given body of stock of a more valuable low boiling point 20 fraction.

Another important object of the invention resides in the provision of means for creating reflux condensation within the fractionating tower in a manner which permits of effective heat interchange between the arising 25 hot oil vapors and the descending liquid condensate, in order that the descending liquids will be subjected to the higher temperature of the arising vapors for the purpose of depriving the condensate of its low boiling point constituents to a maximum degree, and at the same time to lower the temperature of the arising vapors to condense or liquefy and discharge from such vapors the entrained 30 high boiling point constituents thereof, this action being repeated successively until a final and complete separation of the fractions having different boiling points is secured with substantially complete recovery of the different 35 fractions which were present in intermingled form when initially heated and vaporized.

A further object of the invention resides in the provision of a fractionating tower 40 adapted for the refining of petroleum oils, wherein the upper part of the tower is provided with a heat exchanger in the form of a refluxing coil through which the charging stock or other cooling medium is adapted to be circulated for the purpose of controlling

and accurately regulating the outlet temperatures of the tower, whereby the vapors taken overhead from the tower may be so controlled as to minimize the presence therein of oils having higher boiling points than those desired. Another advantage of the refluxing coil resides in the heat economy effected through its use, in that the heat extracted from the hot oil vapors circulating through the tower by the presence of the refluxing coil, is transferred to the incoming charging stock, so as to effect an initial heating of such charging stock prior to its passage through a heating still or the like.

A further object of the invention resides in providing the lower part of the fractionating tower with a second heat exchanger in the form of a reboiling coil. Through this coil there is adapted to be circulated a hot condensate, obtained from any suitable source, which possesses a temperature exceeding that of the reflux condensate which accumulates in the bottom of the tower, in order that the heat radiated or released from the reboiling coil may be used for the purpose of driving off any of the lower boiling point compounds which may be present in the reflux condensate disposed in the bottom of the tower.

A still further object resides in the provision of a drying section in the extreme top of the fractionating tower which is formed to provide a plurality of tortuous passages through which the oil vapors are circulated so as to bring such vapors into contact with extended heating surfaces, which serves to prevent liquid entrainment in the oil vapors passing from the tower.

Still, another object of the invention resides in providing the tower between the reboiling and refluxing sections with a stripping or fractionating section, which comprises a plurality of trays arranged in spaced order and formed to include narrow metallic stampings of trough formation in cross-section, each of said stampings being so designed that it contains a liquid level and at the same time presents the maximum amount of surface for vapor contacts, the troughs or stampings being supported in spaced horizontal rows within the tower, these troughs

or vanes serve to hold a liquid, present a maximum amount of surface for reboiling, and act as baffles to the rising vapors, causing the latter to follow a weaving course while 5 passing upwardly through the tower and serve to provide effective contacts between the ascending vapors and the descending liquid condensate.

A still further object of the invention resides in the provision of distributing pans which cooperate with the troughs or vanes for the purpose of insuring an even distribution of the vapors and reflux throughout the tower, preventing channeling of such vapors 15 in any particular portion of the tower. Further, the arrangement of the pans and troughs permits of free vapor passage without unnecessary restriction so that the vapors may flow through the tower at proper velocity to 20 procure the most beneficial results, a feature which enables the tower to operate to advantage when subjected to pressures both above and below normal atmospheric pressures.

With these and other objects in view that 25 will appear as the description proceeds, the invention consists in the novel features of construction, combinations of elements and arrangements of parts hereinafter to be more fully described and pointed out in the appended claims.

In the accompanying drawings:

Figure 1 is a view in vertical section taken through the lower half of a fractionating tower constructed in accordance with the features of the present invention,

Figure 1a is a similar view showing the upper half of the tower,

Figure 2 is a transverse horizontal sectional view taken on the plane indicated by 40 the line 2—2 of Figure 1,

Figure 3 is a transverse vertical sectional view on the line 3—3 of Figure 1,

Figure 4 is a transverse vertical sectional view on the line 4—4 of Figure 1a,

Figure 5 is a transverse horizontal sectional view on the line 5—5 of Figure 1,

Figure 6 is a similar view taken on the plane indicated by the line 6—6 of Figure 1a,

Figure 7 is a plan view on an enlarged scale 50 disclosing more particularly the construction of the vanes used in the drying section of the tower, as set forth in Figure 6,

Figure 8 is a side elevation of such vanes looking in the direction indicated by the arrow X in Figure 6,

Figure 9 is an edge elevation thereof looking in the direction indicated by the arrow Y in Figure 6,

Figure 10 is a transverse sectional view 60 taken on the plane indicated by the line 10—10 in Figure 1, showing more particularly the formation of the troughs or vanes employed in the fractionating or stripping section of the tower,

Figure 11 is an enlarged transverse verti-

cal section taken through such troughs or vanes on the line 11—11 of Figure 10,

Figure 12 is a detail side elevation of one of the troughs or vanes,

Figures 13 and 14 are detail views.

Referring more particularly to the drawings the numeral 1 designates the improved fractionating tower comprising the present invention in its entirety. In the specific form of the invention disclosed in the drawings and hereinafter described in detail, the tower comprises a cylindrical metallic shell which may be approximately 70 feet in height and 8½ feet in diameter, there being two horizontally disposed drums provided in connection with the tower each of which is 8½ feet in diameter and 16 feet long. It will be understood that these dimensions are given merely for purposes of facilitating an understanding of the invention and may be varied 80 from time to time, depending upon the operating conditions in which the tower is situated.

One of these drums is located at the bottom of the tower and is indicated by the numeral 2 and serves to form a reservoir with large vaporizing surface for the oil which is refluxed to the bottom of the tower when the latter is in operation. A substantial liquid level is maintained in the connection 2 when the tower is in operation by means of any suitable type of liquid level controllers. When it is desirable to utilize heat from some hot stream of oil to assist in obtaining better fractionation, a coil 3 is installed in the section 2 and through which hot oil, obtained from any suitable source, may be passed. The coil 3 has been specifically illustrated in Figures 1 and 3 and, as shown, is supported by means of an angle iron frame work 4, which is first constructed in the bottom of the tower and acts as a support for the various pipes or tubes comprising what is known as the reboiler coil 3. The cross members of the angle iron frame work are bolted together so that they can be easily removed to permit the entire reboiler coil to be taken down for repair or cleaning purposes without interfering with any other portion of the tower.

The coil 3 itself consists in this instance of fifty four inch boiler tubes joined together in series by means of cast steel return bends 5, into which the ends of the tubes comprising the coil 3 are rolled. The return bends have threaded plugs 6 disposed in opposed relation to the tube openings so that access to the tubes is comparatively easy for cleaning or re-rolling. The tubes, in this instance, are assembled in seven planes so arranged in a staggered formation that contact between the fluid passing through the sections and the tubes is very uniform. The fluid dropping into this reboiler section is prevented from circulating around the tubes by sealed skirts 130

7 which project from the top of the horizontal drum 2 down along each side of the tubes. In operation the fluid level in this section is maintained at a point which is preferably just above the top-most coil of the reboiler. This section of the tower is made accessible by manholes 8 arranged at each end, these being staggered so that any single tube comprising the coil 3 may be removed from the shell without disturbing any other tubes.

The other drum 9, disposed in the upper part of the tower, and located about sixteen feet from the top of the tower, contains a heat exchanger or refluxing coil 10 of peculiar design. The coil 10, as herein illustrated, consists of approximately 402 one and one-quarter inch O D cold drawn seamless steel tubes, each of which is about twelve and one-half feet long and the tubes are arranged in three groups as shown, in such a manner that the cold oil passing through the coil 10 is forced to travel from one end of the refluxer to the other, the oil travelling through several parallel tubes. These tubes are rolled into headers 11, which are mounted entirely independently of the supporting structure 12, so that they are free to expand and contract without fracturing any portion of the apparatus. Three groups of tubes are used instead of one large group, so that the tube headers will not be thrown into expansion strains due to the great difference between the temperature of the oils entering and leaving the refluxer tubes. The headers 11 are provided with removable plugs 13, which are arranged in registration with the tubes comprising the coil 10, so that each of said tubes may be removed, cleaned or rerolled without affecting any other tube. This facilitates replacement and cleaning.

The vapor passages through the refluxer are so arranged that the vapors weave back and forward through each group of tubes, as indicated by the arrows in Figure 1a, insuring contact of the vapors with the tubes throughout the exchanger so that all available surface is efficiently used. Sufficient space is provided throughout the vapor portion of this refluxer section of the tower so that the vapors do not increase in velocity while passing through this section, thereby eliminating the possibility of carrying over excessive amount of entrained liquid. As the maximum amount of condensation takes place in this section of the tower, the fact that the velocity of the vapors is not increased is considered to be a very desirable feature. U shaped drains 14 are provided in all parts of the refluxer where fluid would tend to accumulate, so that the condensates are carried back to the bottom of the refluxer without coming into further contact with the vapors. At the same time the liquid seal prevents vapors from by-passing through this drain. The baffle sheets 15 in the refluxer are electric

welded to insure the passage of all the vapors through the tube section of the refluxer. The dead ends of the refluxer formed by the tube supporting sheets, drain back into the fractionating section of the tower through sealed traps or U shaped bends. It will be understood that cold oil, such as charging stock, may be circulated through the refluxing coil by the inlet and outlet connection 16 and that by regulating this volume of cold oil flow the outlet temperatures of the tower may be controlled within exceedingly close limits for the purpose of securing an overhead product of the desired boiling point. At the same time heat economy is present in that the heat extracted from the vapors is transferred to the charging stock, which may be additionally heated in a still or other apparatus for complete vaporization. The section 9 has its ends provided with manholes 17, which provide access to the refluxing section.

The stripping section 18 of the tower is filled with trays 19 of a special design. The stripping section 18 is that portion of the tower between the reboiler section 3 and the vapor inlet conduit 20. The conduit 20 is, of course, connected with a still or other vaporizing apparatus. The fractionating sections 21 of the tower comprise that portion situated between the vapor inlet and the refluxer section 9, the sections 18 and 21 are substantially identical in construction and comprise a plurality of trays 19 and 22 respectively. These trays are made up of narrow steel stampings which, as shown in Figure 11, are substantially trough shaped in cross section. Each tray may be of any suitable length and its trough shaped upper portion is adapted to receive a suitable quantity of liquid, the sides of the trays terminating in transversely spaced depending walls 23. The ends of the trays are received within horizontally extending supports 24 fixed within the tower. The upper edges of the supports are notched so as to receive the trays and to maintain the latter in supported and spaced relationship. As indicated in Figure 11 the trays in adjoining rows are disposed in staggered order so as to secure the most effective contact between the vapors and the trays. In practice, the vanes or trays are assembled outside of the tower and are then lowered into the tower so as to rest upon the I beams or angle clips 25 secured to the inner walls of the tower. The supports 24 are rigidly secured together in a substantial frame work so as to prevent undue separation or loss in operating positions on the part of the vanes or trays. Filler plates 26 are situated between the outer marginal portions of the trays and the inner walls of the tower and prevent vapor passage upwardly through the tower without proper contact with the vanes or trays.

Above each section of vanes or trays there is provided a horizontally disposed pan 27

provided, as shown in Figures 1 and 5, with flow openings 28, the walls of which are defined by upstanding collars 29. The total area of the openings 28 is such as to cause a slight restriction to the passage of the vapors and to thus force the vapors to pass through all of the openings 28. These openings are distributed over the entire cross section of the tower and in this way channeling of the vapors is prevented. Each pan also acts as a distributor for the reflux, there being small dams or reservoirs around each vapor opening 28 produced by the collars 29, the latter being perforated as at 30 slightly below the upper end thereof. The total cross-sectional area of these openings or perforations in the pans is worked out to closely conform to the area required for the passage of the material refluxed to the bottom of the tower. Any excess will run over the edges and be distributed on the vanes below. Due to this construction the efficiency of the fractionating section is greatly increased by insuring distribution of the vapors and reflux throughout the tower. Each succeeding vane section is turned at right angles to the section below which tends further to effect distribution of vapors uniformly throughout the tower.

The stripping section 18 of the tower consists in this instance of ten layers of vanes or trays with a distributing pan between the top layer and the vapor inlet. The fractionating section 21 consists of three packs, each composed of twenty layers of vanes with a distributing pan above each pack. The trays in the fractionating section of the tower maintain constant fluid levels throughout the tower, the total liquid so retained being in excess of that held on the trays in other towers of this character. This fluid or liquid content of the fractionating section permits of finer control as it is necessary to vaporize or cool a large amount of fluid in order to obtain any great temperature changes in the tower. The vapor to liquid contact is positive, but at the same time, on account of the open character of the tower, the friction caused by the vapors rising through the rain of reflux from the trays is almost negligible. The open nature of the tower makes it particularly well adapted to low pressure operation and may be adapted with commensurate efficiency to vacuum distillation processes. In this connection it may be stated that the commonly used bubble type tower requires a differential pressure through each tray and therefore will probably never be well adapted to high vacuum distillation. This feature also makes the bubble tower undesirable for use with apparatus which is not so designed to withstand high pressures. The present fractionating tower, comprising the present invention, has been found to be very flexible as it operates with practically the same efficiency with a great variation in the amount

of oil put through. It is practically impossible to flood the tower or to cause it to prime.

Above the refluxer section 9 there are disposed in this instance twelve trays 31 of the same design as those used in the fractionating section, and above the trays 31 and in the top dome 32 of the tower there is arranged what is termed a drying section 33. This section consists of a number of vanes, indicated at 34 in Figures 7 to 9. These vanes are set vertically in rows, with each succeeding row staggered, as shown in Figure 7. This arrangement forms a labyrinth baffle through which the vapors are forced to pass in a circuitous course. The velocity is increased somewhat through the drying section so that any fluid entrained in the vapors will be impinged against the vanes 34, and as the vapors must reverse in order to find their way out of the baffle, the liquid is given an opportunity to run down at the corners of these baffles, where it drains into a pan 35 which, in turn, is drained back to the refluxer section. The use of this drying section serves, therefore, to minimize liquid entrainment in the vapors which pass off overhead from the tower by way of the outlet 36 provided in the dome 32.

The manufacture of the tower thus described is relatively simple since the parts composing the fractionating and drying sections are stamped from flat strips of steel and can be produced at low cost very quickly. The manner of construction of the various sections permits of very rapid assembly. The fractionating portion of the tower can easily be dismantled for cleaning, should this operation be necessary, and the different parts of the tower are accessible by the manholes provided in the connections 2 and 9.

The fractionating tower thus described is particularly well adapted for petroleum refining processes and may be used in straight still distillation processes or in connection with petroleum cracking processes where relatively high temperatures and pressures are utilized, also, in connection with both liquid and vapor phase methods of petroleum conversion. It will be understood that in the operation of the tower the heated vapors, obtained from any suitable source, enter the tower by way of the inlet conduit 20 and ascend through the tower, coming first into contact with the baffles or vanes of the fractionating sections 21, wherein the constituents of high boiling point condense by coming into contact with the cooler metallic surfaces of the trays 22 arranged within said fractionating section and also with descending reflux condensate. The vapors of lower boiling points after passing through the fractionating section come into contact with the reflux coil wherein a greater temperature differential obtains, the passing of cold oil through the refluxing coil serving to absorb the heat

from the ascending vapors and to reduce their temperature sufficiently to liquefy the heavier constituents so that the latter will drop back into the lower part of the tower. The vapors not condensed by the refluxing coil pass up and outwardly from the tower by way of the trays 31 and the drying sections 33, the vapors passing overhead from the tower by the outlet 36. This outlet may lead to additional fractionating towers or may pass through a cooling coil so as to conduct the vapors and to permit of their use for any suitable purpose. The passage of the first charging stock through the refluxing coil is preferably under automatic control so that the temperature of the out-going vapors may be very carefully regulated to procure a maximum recovery of petroleum fractions of specified boiling points. In other words by carefully regulating this temperature the tower is capable of sharply separating gasoline and kerosene fractions. This is likewise true as regards gasoline and naphtha, or kerosene and gas oil, or gas oil and wax distillate. In this connection it should be observed that one or more of the fractionating towers may be used in connection with a distillation or fractionating system to obtain any desired number of cuts or fractions from a given body of oil. Preferably, the towers are arranged in series with the heavier products removed from the bottom of each tower and the lighter products from the top thereof. Thus the liquefied and heavy bottoms of one tower may be circulated through the reboiling coil 3 in the next adjacent tower, thereby procuring high heat economy and an efficiently operating system. The reflux liquid gradually descends within the tower passing, for example, from the refluxing coil into the fractionating section, wherein all of its lighter constituents are released by the upwardly moving vapors. The reflux condensate then settles into the stripping section arranged below the vapor inlet, and finally this reflux condensate collects in the bottom of the tower around the surfaces of the reboiling coil 3, where the oil is additionally heated by the hot oil circulating through the reboiling coil for the purpose of insuring the maximum recovery of all of the low boiling compounds which may be present in the reflux condensate by the time the latter reaches the bottom of the tower. As previously stated, this reflux condensate which accumulates in the bottom of the tower may be removed for storage purposes or in the course of its removal may be circulated through the reboiling coil of an adjacent and complimentary tower for the purpose of utilizing to the fullest extent the heat which may be present therein.

What is claimed is:

1. In liquid and vapor contacting apparatus, a plurality of relative superposed rows of horizontally disposed open topped liquid re-

taining trays, a vertically disposed shell having a vapor inlet and a vapor outlet formed therein between which inlet and outlet said trays are mounted, the trays of each row being disposed in parallel relatively spaced relationship and laterally offset with respect to and spaced from the trays in the next adjoining upper and lower rows, notched spacing bars for positively maintaining the trays in such spaced relationship, and a supporting frame formed for the removal and unitary support of said trays and bars. 70 75

2. In liquid and vapor contacting apparatus, a plurality of relative superposed rows of horizontally disposed open topped liquid retaining trays, a vertically disposed shell having a vapor inlet and a vapor outlet formed therein between which inlet and outlet said trays are mounted, the trays of each row being disposed in parallel relatively spaced relationship and laterally offset with respect to and spaced from the trays in the next adjoining upper and lower rows, and notched spacing bars extending at right angles to said trays for maintaining the latter in such spaced relationships, the lower edges of said bars resting upon the upper edges of the next lower row of trays, the notches in said bars serving to maintain the trays supported thereby secure against movement longitudinally of the bars. 80 85 90 95

3. In liquid and vapor contacting apparatus, a plurality of relative superposed rows of horizontally disposed open topped liquid retaining trays, a vertically disposed shell having a vapor inlet and a vapor outlet formed therein between which inlet and outlet said trays are mounted, the trays of each row being disposed in parallel relatively spaced relationship and laterally offset with respect to and spaced from the trays in the next adjoining upper and lower rows, and spacing devices extending substantially at right angles to said trays for positively maintaining the latter in the spaced relationship specified, said devices being supported by the upper portions of the trays provided in the next adjacent lower row. 105 110

4. In liquid and vapor contacting apparatus, a plurality of vertically superposed horizontal rows of longitudinally extending relatively spaced liquid retaining trays, the trays of each row being disposed in parallel relatively spaced relationship and offset laterally with respect to and spaced from the trays in the next adjoining upper and lower tray rows whereby tortuous passages are provided between said trays, supporting and spacing devices for maintaining said trays in unitary assembly and spaced relationship, and an imperforate jacket surrounding the tray assembly and operating to confine fluids to substantially vertical travel through the tray assembly. 115 120 125

5. In liquid and vapor contacting appa-

- ratus, a plurality of vertically superposed horizontal rows of longitudinally extending relatively spaced liquid retaining trays, the trays of each row being disposed in parallel 5 relatively spaced relationship and offset laterally with respect to and spaced from the trays in the next adjoining upper and lower tray rows whereby tortuous passages are provided between said trays, supporting and 10 spacing devices for maintaining said trays in unitary assembly and spaced relationship, an imperforate jacket surrounding the tray assembly and operating to confine fluids to substantially vertical travel through the tray assembly, and a distributing pan arranged over the tray assembly in a horizontal plane, said pan being provided in the bottom thereof with a plurality of outlets formed to retain a liquid level in the bottom of said tray.
- 15 6. In fractionating apparatus, a shell, a vapor inlet in the lower part of said shell and a vapor outlet in the upper part of said shell, a frame mounted stationarily within said shell between the vapor inlet and outlet, said 20 frame including a plurality of cross members having registering notches provided therein, and a plurality of horizontally extending trays arranged in vertically superposed rows, the ends of said trays being receivable within the notches provided in said cross members, the notches in said cross members being so disposed that the trays of adjoining rows are arranged in staggered relationship.
- 25 7. In a fractionating tower, a shell, a vapor inlet in the bottom of said shell and a vapor outlet near the top of the shell, a fractionating section between the vapor inlet and outlet consisting of a plurality of superposed groups of nested trays, each group comprising a plurality of horizontally arranged rows 30 of trays arranged in relatively spaced offset order to produce tortuous vapor passages through and between the trays, each of said trays being formed to include a trough for the reception of liquid condensate, apertured distributing pans arranged immediately over each group of trays and a structural framework for supporting the trays stationarily within said shell.
- 35 8. A fractionating tower comprising a shell of substantially closed hollow form, a vapor inlet in the lower part of said shell, and a vapor outlet in the upper part of said 40 shell, a heating coil situated in the bottom of said shell, a cooling coil in the upper part of said shell, stripping baffles stationarily mounted in said shell between said vapor inlet and said heating coil, stationary groups 45 of fractionating baffles mounted within said shell between said vapor inlet and said cooling coil, a plurality of vertically arranged drying baffles situated in the upper part of said shell between said cooling coil and said 50 vapor outlet and means for causing the 45 vapor to travel laterally and upwardly through said drying baffles.
- 55 9. A fractionating tower comprising a substantially hollow and closed body, a vapor inlet in the lower part of said body and a vapor outlet in the upper part thereof, said body having the lower portion thereof formed to include a liquid receiving reservoir, a heating coil suspended within said reservoir, inlet and outlet connections formed 70 with said coil and leading exteriorly of said body to permit of the circulation of a heating medium through said coil, means for withdrawing liquid from said reservoir, a cooling coil situated in said body between said vapor inlet and outlet, inlet and outlet connections connected with said cooling coil for admitting of the circulation of a cooling medium through said cooling coil, a group of stripping baffles arranged within said body 75 between the heating coil and the vapor inlet, vertically superposed groups of fractionating baffles between said vapor inlet and said cooling coil, a group of vertically arranged drying baffles between said cooling coil and 80 said vapor outlet and means for causing the vapors to travel laterally and upwardly 85 through said drying baffles.
